(57) **CLAIM**

The ornamental design for the front panel comprising a card-slot, as shown and described.

DESCRIPTION

FIG. 1 is a front view of a front panel comprising a card-slot showing my new design;

FIG. 2 is a top view thereof;

FIG. 3 is a left side view thereof;

FIG. 4 is a right side view thereof;

FIG. 5 is a bottom view thereof; and,

FIG. 6 is a rear view thereof.

The broken lines are shown in FIGS. 2-6 for illustrative purposes only and form no part of the claimed design.
